UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN-CONTROL SYSTEM.

Application filed April 1, 1916, Serial No. 88,365. Renewed November 23, 1925.

To all whom it may concern:

Be it known that I, WINTHROP K. HOWE, a citizen of the United States, and a resident of the city of Rochester, in the county of Monroe and State of New York, have invented a new and useful Automatic Train-
Control System, of which the following is a specification.

This invention relates to systems for automatically governing the movement of railway trains.

In the practical operation of railroads there are conditions which make it desirable in designing an automatic train control system to provide for two kinds of control for trains, for the reason that at some parts of the railroad the purpose of the system is to prevent collisions between trains on the same track, whereas at other parts of the railroad, such as at yards, crossings and the like, the purpose of the system is to prevent interference or collision between trains on converging or intersecting tracks. In one case where the trains are on the same track, practical operating conditions seem to be satisfied if a train is permitted to enter a portion of track which may be occupied by another train, providing the first train proceeds slowly and cautiously; or, in other words, it is permissible for a train to pass a signal indicating stop or danger where the danger consists in the likelihood of meeting some other train on the same track. On the other hand, when a train approaches a place where there are converging or intersecting tracks and the right of way has been given to some other train, it should not be possible for the first train to pass the signal at stop which indicates this fact, otherwise said first train, even if it were proceeding slowly and cautiously, might cross the path of another train, which relying on the proceed indication given to it, might be moving fast. The distinction between two different kinds of control which may be termed absolute control and permissive control, has been recognized in railway signaling for some time and is found in signaling systems as they are generally installed at the present day, in that so-called permissive signals when indicating stop or danger may be passed by an engineer after observing certain prescribed rules and regulations, whereas the so-called absolute signals indicating stop or danger located at portions of the track

governed by an interlocking plant may not be properly passed by an engineer without special permission. In automatic train control systems, however, this distinction has not been observed and followed, and in general in the automatic train control systems heretofore developed no distinction has been made between the kind of controlling effect which should be produced on a train at different parts of a railroad; and furthermore, the means used for communicating information from the track to the train has been of the same characteristics throughout the length of the railroad;

It is contemplated according to this invention to make suitable provisions for the two kinds of control above mentioned, and one of the principal objects of the invention is to devise an arrangement of devices and controlling circuits therefor which will efficiently and reliably afford the two kinds of control at any required places along a railroad track without requiring the use of complicated apparatus.

Another object of the invention is to devise a system for automatically controlling railway trains in which both the absolute and the permissive controls are accomplished by the cooperation of contact shoes carried by the train with ramps or contact rails located along the track.

Another object of the invention is to arrange the absolute control of the train which acts to bring the train to an absolute stop so that, while this absolute control will be produced effectively and reliably, it is not likely to occur accidentally.

Another object of the invention is to make provision for automatically displaying a distinctive signal on board a train when and so long as this train moves in the direction opposite to the normal direction of traffic, and to arrange the control of this signal such that it may be operated by the same ramps and contact shoes which are utilized for governing the movement of the train.

Other objects and advantages will appear as the description of the invention progresses, and the novel features of the invention will be particularly pointed out in the appended claims.

In the accompanying drawing, wherein I have illustrated a preferred physical embodiment of my invention, and wherein like characters of reference designate corre-

sponding parts through the several views, and in which:

Fig. 1 is a diagrammatic view of the parts and controlling circuits embodying this invention and constituting a system for automatically controlling railway trains, these parts being shown more with a view to make the functions and correlation of the parts controlling circuits clear than with a view to showing the exact construction and arrangement of these parts; and Fig. 2 is a diagrammatic view of suitable trackway circuits for assumed conditions suitable to illustrate the features and operation of the system.

Referring to Fig. 1, 1 and 2 designate portions of the track rails of a railroad, which are supported upon ties in the usual manner and which are broken away for the sake of clearness. To illustrate the characteristics and operation of a system embodying the invention, a single car or locomotive is shown diagrammatically in Fig. 1 as comprising a front pair of wheels 3—3 connected by the usual axle 4 and a rear pair of wheels 5—5 connected by the axle 6, it being understood that the axles 4 and 5 are in practice connected by a suitable frame (not shown). Communication between the track and the vehicle is obtained by suitable contact shoes and ramps; and in the particular embodiment illustrated two contact shoes S and S¹ are carried by the vehicle on opposite sides and at opposite ends, and since the construction of these contact shoes is the same, a description of one will suffice for both, the same reference characters being used for the parts associated with the shoe S¹ as for those associated with the shoe S, with the distinctive exponent "1" added thereto. For simplicity each contact shoe is shown supported by a suitable bracket 7 assumed for simplicity to be of insulating material, and each contact shoe comprises a foot or contacting portion, designated S which is pivotally connected to the lower ends of two angle levers 8 and 9, said angle levers being mounted upon the bracket 7 for rocking movement in a vertical plane. Attached to the end of the upper arm of the angle lever 9 but insulated therefrom is a contact piece 11. When the shoe is not in engagement with a ramp it is in the position shown in Fig. 1, and the upper arms of the angle levers 8 and 9 extend substantially horizontally. Each contact shoe is designed not only to make electrical contact with the successive ramps with which it engages, but also to open and close certain circuits selectively depending upon the direction of movement of the vehicle. In order that the shoe may perform this latter function, two vertically movable contact carrying rods 12 and 13, assumed for simplicity to be made of in-

sulating material, are slidably mounted in suitable supports or guides 14 and 15 secured to the bracket 7. The lower end portions of the rods 12 and 13 are reduced in diameter to form shoulders which strike the guides 14 and limit the downward movement of said rods. The rods 12 and 13 have a tendency, due to their weight, or aided by a spring or other means, (not shown), to move to their lower position as shown in Fig. 1; and are arranged one above each of the upper arms of the angle levers 8 and 9 so that, as shoe S is moved lengthwise of the vehicle and upward in one direction, one of said rods is raised, while if the shoe is moved similarly in the other direction, the other rod is raised. Connected to the rod 12 are suitable circuit controlling contact fingers, designated 16, 17, 18 and 19, the contacts cooperating with said contact fingers being represented by arrows; and in the same way the rod 13 is provided with two contact fingers 20 and 21.

The ramps R for cooperating with the contact shoes S and S¹ may be of any suitable construction and are shown as metallic members with sloping ends which are mounted adjacent to the track rails 1 and 2 upon suitable insulating supports, it being understood that these ramps are arranged in the same plane as the contact shoes so that, when a contact shoe engages with a ramp, said shoe is moved rearwardly relatively to the vehicle and also upwardly and one or the other of the rods 12 or 13 is lifted by the angle lever 8 or 9. According to this invention it is contemplated that the ramps in most cases will be located upon one side of the track, which in the particular embodiment illustrated is the righthand side for the normal direction of traffic; except at the points where it is desired to be able to bring the train to an absolute stop, at which points a ramp is located on each side of the track. In some cases it may be found desirable to operate trains in both directions over a stretch of single track and this may be accomplished by placing the ramps on each side of the track and by arranging a suitable means, automatic or manually operated, whereby a certain difference of potential is established between the ramps on one side of the track at all times while a train is passing through the stretch in the direction opposite to the direction of traffic governed by these ramps, and whereby the difference of potential between the respective ramps on the other side of the track is controlled by the track circuit sections of the stretch of track according to traffic conditions in the same way as more fully explained herein-after.

The trackway circuits for controlling the difference of potential between the ramps and the track rails are not shown in Fig. 1,

and for simplicity it is assumed that this difference of potential is derived from a suitable alternating current generator G, to which is connected by wires 22 and 23 the primary of a transformer T^2 , and also to which is connected by wires 24 and 25 the primary of a transformer T^1 . The connections between the secondaries of the transformers T^1 and T^2 are the same in most respects and the same reference characters are used for these connections of the transformer T^2 as for the transformer T^1 , with the exponent "1" added thereto. One terminal of the secondary of the transformer T^1 is connected by a conductor 29 to the track rail 2, and the other terminal of said secondary is connected by a conductor 28, switch 26 and conductor 27 to the ramp R. The switch 26 is arranged so that it may 10 break connection with the conductor 28 and make connection with a conductor 30 leading to an intermediate point in the winding of the secondary of the transformer T^1 . When the switch 26 is in the position shown 15 in Fig 1, a difference of potential equivalent to the entire voltage of the secondary of the transformer T^1 is established between the ramp R and the track rail 2; whereas, when the switch 26 is moved to make contact with 20 the conductor 30, a difference of potential equivalent to only part of the voltage of the secondary T^1 is established between said ramp and said track rail. The difference of potential between the ramp R and the track 25 rail 1 which is derived from the entire voltage of the secondary of the transformer T^1 will be hereinafter termed for convenience high voltage on the ramp R; whereas the difference of potential derived from part 30 of said secondary will be hereinafter termed low voltage on the ramp R. The switch 26 may also be moved out of contact with both 35 of the conductors 28 and 30, so that no difference of potential will exist between the ramp R and the track rail 2; and this 40 condition of the ramp R will hereinafter be referred to for convenience as no voltage on the ramp.

The permissive control of the movement of 45 the train or vehicle may be obtained by any suitable device, preferably some device or apparatus which acts to control the speed of the train or vehicle rather than to cause an immediate application of the brakes. Also, 50 the device may be merely a signal to guide the operator of the vehicle, or it may be an automatic device capable of giving a delayed application of the brakes, subject to the intervention of the operator. Various 55 kinds of speed control apparatus capable of performing the functions necessary for this invention are well known in the art, and it is considered unnecessary for the purpose of a clear understanding of this invention to

show and describe in detail such a speed 65 control apparatus, this apparatus for convenience and simplicity being shown conventionally and designated SC. One such type of speed control apparatus is disclosed in my prior application, Ser. No. 38,132, filed 70 July 6, 1915. The speed control apparatus SC is controlled by a control relay K having armatures 31, 32 and 33, represented according to established convention; and the control relay K in turn is controlled at times 75 by an alternating current relay 34 having an armature 35, the relay 34 being preferably designed to be immune to direct current 80 carried on the vehicle or by the current which may be used for propelling the vehicle.

For the purpose of explaining this invention it is assumed that the vehicle or train 85 is equipped with pneumatic brakes of the ordinary type, which include a train pipe designated in Fig. 1 as 120; and since the operation and construction of the pneumatic system of brakes is well known, it is considered to be unnecessary for the purposes of explaining this invention, to show and describe in detail this system of brakes, it being merely necessary for a clear understanding of this invention to know that the 90 brakes are applied on the train or vehicle when the train pipe 120 is vented. It is contemplated according to this invention, although the invention is in no wise restricted to such an arrangement, that the speed control apparatus SC will control the brakes and cause the so-called service application of said brakes whenever the actual speed of the vehicle exceeds a permissive speed for 95 the vehicle at that time; and that the absolute control, consisting in bringing the vehicle to an absolute stop, is obtained by causing an emergency application of the brakes. In the particular arrangement illustrated 100 diagrammatically in Fig. 1, a suitable electrically operated valve EB controls communication between the train pipe 120 and the outside air and is constructed so that, when deprived of its normal energizing current, said valve will be opened to such an extent as to vent the train pipe 120 sufficiently and rapidly enough to cause an 105 emergency application of the brakes.

The valve EB controlling the emergency 110 application of the brakes is controlled by a stop relay E having two armatures 36 and 37; and said stop relay E in turn is controlled at times by a relay 38 having an armature 39. The relay 38 is similar to the relay 34 and is likewise preferably designed 115 so as to be immune to direct current.

The relays 34 and 38 have controlling circuits so as to be responsive to current flow-

ing from a ramp to a shoe, and thence through the frame of the vehicle and its wheels and axle to the track rail; but in order to insure that direct current may not 5 find its way to the relays 34 and 38 from the ramps, transformers designated TS and TE for controlling the relay 34 associated with the speed control apparatus and the relay 38 associated with the emergency stop 10 apparatus, respectively, are interposed in the connection between said relays 34 and 38 and the contact shoes.

It sometimes happens in the practical operation of railroads that it is necessary for 15 a locomotive, motor car or entire train to run over a track in the direction opposite to the normal direction of traffic, and in such a case the vehicle or train making this against traffic move will generally have 20 no signals to guide it. In order that the engineer or motorman of a train making a move against the normal direction of traffic may be constantly reminded of the fact that his train is making an abnormal move- 25 ment, it is desirable to display before him a distinctive signal, designated in Fig. 1 as NS, which signal may be a colored light, an illuminated sign, movable indicator or the like. The no-signal device NS is con- 30 trolled by a relay N having two separate windings 100 and 101 and two armatures 114 and 121. The devices on the vehicle or train are supplied with current from any suitable source, as a battery F. The dif- 35 ferent conductors and electrical connections between the different controlling devices will not be described in detail, since the different circuits set up during the operation will be fully described hereinafter. In describ- 40 ing the operation occasion will be had at times to refer to certain circuits which have already been traced; and in order to avoid unnecessary repetition, each of the circuits as it is traced will be given a designating 45 number and will thereafter be referred to by that number. In view of the number of circuits involved and their peculiar functions, it seems expedient to give a brief statement in tabular form of the numbers of 50 the circuits and their functions as follows:

Circuit number	Function performed	
Ten	Partial circuit associated with shoe S ¹ and including the primary of the transformer TE for energizing the relay 38.	70
Eleven	Energizes the stop relay E when the relay 38 is energized.	
Twelve	Partial circuit associated with the shoe S and including the primary of the transformer TE for energizing the relay 38.	
Thirteen	Circuit closed by the operation of the shoe S for preliminarily energizing the no-signal relay N.	
Fourteen	Partial circuit closed by the operation of the shoe S ¹ for preliminarily energizing the no-signal relay N.	75
Fifteen	Circuit for maintaining the no-signal relay N energized.	
Sixteen	Energizes the no-signal device NS.	

Before considering the arrangement of circuits along the track as shown in Fig. 2 for properly controlling the vehicle in accordance with traffic conditions, the operation of the parts of the system on the vehicle will be considered first. Referring to Fig. 1, the parts are shown in their normal position, and disregarding for the moment the manner in which these parts are placed in their normal position, assume that a vehicle equipped with the parts constructed as shown in Fig. 1 is running over a stretch of track where it is only necessary to control the speed of the vehicle.

Operation of the speed control apparatus.

When the parts are in their normal position the control relay K is energized by current supplied from the local battery F on the vehicle by a circuit which may be traced as follows:

Circuit Number One.

Commencing at the battery F, conductors 40, 41, 42, 43 and 44, control relay K, conductors 45 and 46, armature 31 of said relay in its upper position, conductor 47, contact finger 18 in its lower closed position, conductor 48, contact finger 18¹ in its lower closed position, and conductors 49, 107, 50 and 51 back to the battery F.

When the control relay K is energized and its armature 33 is in its upper position, current is supplied from the battery F to the speed control apparatus SC which, according to the construction preferably employed for said speed control apparatus, retains this apparatus in its idle condition, the circuit for accomplishing this result being traced as follows:

Circuit Number Two.

Commencing at the battery F, conductors 40, 41, 42, 43, 52 and 53, apparatus SC, conductor 54, armature 33 of the control relay K in its upper position, and conductors 55, 56, 57, 58, 59 and 51 back to the battery F.

Assume that a vehicle having its control relay K energized and its speed control apparatus SC in its normal condition, approaches a ramp R on the righthand side of

Circuit number	Function performed
One	Normally energizes the control relay K.
Two	Normally energizes the speed control apparatus SC.
Three	Partial circuit associated with the shoe S including the primary of the transformer TS for energizing the relay 34.
Four	Energizes the control relay K when the relay 34 is energized.
Five	Partial circuit on the vehicle associated with the shoe S ¹ including the primary of the transformer TS for energizing the relay 34.
Six	Normally energizes the valve EB and is controlled by stop relay E.
Seven	Auxiliary circuit for energizing the valve EB when the control relay K is energized.
Eight	Normally energizes the stop relay E when the shoe S is in its normal position.
Nine	Normally energizes the stop relay E when the shoe S ¹ is in its normal position.

the track traveling in the normal direction of traffic indicated by the arrow X. When the righthand shoe S engages the ramp R it is swung to the left as viewed in Fig. 1 and upward, and the angle lever 8 raises the rod 12 and lifts the several contact fingers carried by said rod. The lifting of the contact finger 18 breaks the Circuit Number One and thereby deprives the control relay K of the current normally supplied to it from the battery F, so that unless the control relay K is supplied with current along some other circuit its armature 33 will drop and set the speed control apparatus SC into operation. The control relay K is supplied with a substitute current by the operation of parts and controlling circuits as follows:

When the shoe S is operated, the contact finger 19 is raised and completes a partial circuit terminating at the shoe S and the axle 6 and including the primary of the transformer TS, said circuit being traced as follows:

Circuit Number Three.

Commencing at the shoe S, conductors 60 and 61, contact finger 19 in its upper closed position, conductors 62 and 63, primary of the transformer TS, and conductors 64 and 65 to the axle 6.

When alternating current flows in the primary of the transformer TS alternating current is induced in the secondary of said transformer, as will be apparent to those skilled in the art, and this induced current flows along conductors 66 and 67 through the relay 34. The relay 34 is constructed so that it is responsive to currents of different intensities; but since relays capable of performing this function are well known in the art, it is deemed unnecessary to illustrate and describe in detail the construction of the relay 34. If the switch 26 is in the position shown in Fig. 1 and the entire voltage of the secondary of the transformer T¹ is established across the ramp R and the track rail 2, the current flowing in the primary of the transformer TS induces sufficient current in the secondary of said transformer to energize the relay 34 sufficiently to raise its armature 35 from its lower position. If the switch 26 is in contact with the conductor 30, however, so that only a medium voltage exists between the ramp R and the track rail 2, the current supplied to the relay 34 is not sufficient to raise the armature 35 from its lower position, but is sufficient to hold said armature in its upper position if it is already there. Obviously, if the switch 26 is disconnected from both wires 28 and 30 and no current is supplied to the relay 34, the armature 35 of said relay will remain in its lower position.

From the foregoing it can be seen that the armature 35 of the relay 34 may be raised, held in its upper position if it is already there, or not raised, according to the intensity of the difference of potential existing between the ramp R and the track rail 2. The manner in which these different voltages are supplied to the ramps in accordance with traffic conditions will be pointed out more fully hereinafter in connection with the description of the trackway circuits shown in Fig. 2.

When the armature 35 of the relay 34 is in its upper position, the control relay K is energized by a circuit traced as follows:

Circuit Number Four.

Commencing at the battery F, conductors 40, 41, 42, 43 and 44, control relay K, conductors 45 and 68, armature 35 of the relay 34 in its upper position, and conductors 69, 58, 59 and 51 back to the battery F.

In this way, when the shoe S engages the ramp R to which high voltage is supplied, the control relay K is maintained in its energized condition, and continues to be energized, although the voltage on the ramp R is later reduced to the medium voltage, since this medium voltage is sufficient to hold the armature 35 of the relay 34 in its upper position after it has once been placed there. Likewise, if the control relay K is deenergized at the time the shoe S engages a ramp R having a high voltage supplied thereto, the control relay K will be energized to restore the parts of the speed control apparatus to their idle condition; and said control relay will remain energized even though the voltage is later reduced to the medium voltage. When the high voltage on the ramp R is later reduced to no voltage while the contact shoe S engages said ramp, the control relay K is deenergized and the speed control apparatus set into operation; and if there is medium voltage or no voltage on the ramp R when the contact shoe S first engages said ramp, the control relay K will be deenergized or will remain deenergized as the case may be. The armature 31 of the control relay K is included in the Circuit Number One for normally energizing said control relay, so that after this control relay has become deenergized, this armature 31 drops and prevents the re-establishment of the Circuit Number One by the movement of the contact finger 18 back to its lower position as the result of the shoe S leaving engagement with the ramp R.

It may happen that the locomotive or motor car equipped with the system shown in Fig. 1 may be turned around on the track with its other end foremost, that is, may be headed in an opposite direction from that shown in Fig. 1, and be traveling at the same time in the normal direction of traffic

indicated by the arrow X. In this case, the shoe S^1 would become the righthand shoe and would engage with the ramp R on the righthand side of the track; and this engagement would serve to swing the shoe S^1 to the right, as viewed in Fig. 1, to lift the righthand rod 12¹ and raise the contact finger 18¹, thereby interrupting the Circuit Number One in the same way as the operation of the shoe S interrupts said circuit. Likewise, when the rod 12¹ of the shoe S^1 is raised and the contact finger 19¹ is in its upper position, a partial circuit is established between the shoe S^1 and the axle 6 and including the primary of the transformer TS, which circuit is similar to the Circuit Number Three hereinbefore traced, and may be traced as follows:

20 *Circuit Number Five.*

Commencing at the shoe S^1 , conductors 70 and 71, contact finger 19¹ in its upper position, conductors 72 and 63, primary of the transformer TS, and conductors 64 and 65 to the axle 6.

From the foregoing it is apparent that the shoe S^1 can be used to accomplish the same controlling functions as the shoe S if the locomotive or motor car is headed in the other direction and is traveling in the normal direction of traffic.

Operation of the absolute stop mechanism.

35 When the parts are in their normal position as shown in Fig. 1, the valve EB controlling the emergency application of the brakes is normally energized by a circuit traced as follows:

40 *Circuit Number Six.*

Commencing at the battery F, conductors 40 and 73, valve EB, conductors 74 and 75, armature 37 of the stop relay E in its upper position, and conductors 76, 77, 59 and 51 back to the battery F.

The valve EB is also energized when the parts are in their normal position by an auxiliary circuit controlled by the control relay K, said auxiliary circuit being traced as follows:

Circuit Number Seven.

55 Commencing at the battery F, conductors 40 and 73, valve EB, conductors 74 and 78, armature 32 of the control relay K in its upper position, and conductors 56, 57, 58, 59 and 51 back to the battery F.

60 The stop relay E is normally energized when the shoe S in its normal position by a circuit traced as follows:

Circuit Number Eight.

65 Commencing at the battery F, conductors

40, 41 and 79, stop relay E, conductors 80 and 81, armature 36 of relay E in its upper position, conductors 82 and 83, contact piece 11 closed, and conductors 84, 85, 57, 58, 59 and 51 back to the battery F.

In a similar way the stop relay E is energized when the shoe S^1 is in its normal position by a circuit traced as follows:

75 *Circuit Number Nine.*

Commencing at the battery F, conductors 40, 41 and 79, stop relay E, conductors 80 and 81, armature 36 of the relay E in its upper position, conductors 82 and 86, contact piece 11¹ closed, and conductors 87, 85, 57, 58, 59 and 51 back to the battery F.

It can be seen from the two circuits last traced that the stop relay E is energized when either of the shoes S or S^1 is in its normal position and is deprived of current only when both of said shoes are operated. When both of the shoes S and S^1 are operated and the stop relay E is deprived of current along Circuits Numbers Eight and Nine, said relay

E may be maintained energized by supplying a substitute current thereto by energizing the relay 38 and raising its armature 39. The relay 38 is energized when current is supplied to the primary of the transformer TE, and said primary of the transformer TE is supplied with current when a shoe on the lefthand side of the vehicle engages an energized ramp on the lefthand side of the track as regards the direction of movement of the vehicle. That is, assuming the vehicle to be traveling in the normal direction of traffic indicated by the arrow X and that the lefthand shoe S^1 engages the lefthand ramp R¹, when the switch 26¹ is in contact with the conductor 30¹ and a medium difference of potential exists between the ramp R¹ and the track rail 1. Under these circumstances the shoe S^1 is swung to the left, as viewed in Fig. 1, the rod 13¹ is lifted and the contact finger 21¹ is raised, thereby establishing a partial circuit including the shoe S^1 and the primary of the transformer TE and the axle 6, said partial circuit being traced as follows:

70

80

85

90

95

100

105

110

115

120

125

Circuit Number Ten.

Commencing at the shoe S^1 , conductors 70 and 92, contact finger 21¹ in its upper closed position, conductors 93 and 90, primary of the transformer TE and conductors 91 and 65 to the axle 6.

Current flowing in the primary of the transformer TE induces a current in the secondary of said transformer which flows along conductors 94 and 95 through the relay 38, thereby energizing the relay 38 and raising its armature 39.

When the armature 39 of the relay 38 is in its upper position, current is supplied

130

to the stop relay E from the battery F along a circuit traced as follows:

Circuit Number Eleven.

- 5 Commencing at the battery F, conductors 40, 41 and 79, stop relay E, conductors 80 and 97, armature 39 of the relay 38 in its upper position, and conductors 96, 77, 59 and 51 back to the battery F.
- 10 It may happen that the vehicle shown in Fig. 1 may be headed in the other direction, although traveling in the normal direction of traffic indicated by the arrow X; and in this case the shoe S, now the righthand shoe, 15 would then be the lefthand shoe and would be in position to engage the lefthand ramp R¹. When the shoe S becomes a lefthand shoe and engages the ramp R¹ it is swung to the right, as viewed in Fig. 1, so that the 20 rod 13 is lifted and the contact finger 20 is raised to its upper position, thereby establishing a partial circuit similar to the partial circuit number ten, hereinbefore traced, which may be traced as follows:
- 25

Circuit Number Twelve.

- 30 Commencing at the shoe S, conductors 60 and 88, contact finger 20 in its upper closed position, conductors 89 and 90, primary of the transformer TE, and conductors 91 and 65 to the axle 6.

In the particular arrangement of controlling circuits shown in Fig. 1, the emergency application of the brakes depends upon a 35 previous deenergization of the control relay K and the operation of the speed control apparatus SC, followed by the concurrent engagement of the shoes S and S¹ with ramps on each side of the track, the lefthand ramp R¹ having no voltage applied thereto and the righthand ramp R having either no voltage or only medium voltage applied thereto. The manner in which these particular conditions are produced will be pointed 40 out hereinafter in describing the trackway circuits shown in Fig. 2.

45 As pointed out hereinbefore, it is desirable to give a distinctive indication to the engineer or motorman when his train is traveling in a direction opposite to the normal direction of traffic, and this result is accomplished by energizing the no-signal relay N. Not only should the no-signal indication be given, but also suitable provision 50 should be made for preventing the operation of either the speed control apparatus or the emergency application of the brakes. As explained hereinbefore, the speed controlling ramps are assumed to be located, except in 55 the case of single track, on the righthand side of the track, so that when a vehicle is making a move against the normal direction of traffic, that is, is moving in an opposite direction to that indicated by the arrow X, 60 the righthand shoe S engages a righthand

ramp R and, due to the reversed movement of the vehicle, said shoe S is moved to the right as viewed in Fig. 1. It is apparent that this righthand movement of the shoe S does not raise the circuit controlling rod 12, 70 and consequently, the contact finger 18 is undisturbed and maintains the Circuit Number One closed. In this way, a train may travel through a stretch of track in the direction opposite to the normal direction of traffic without having its speed control apparatus affected.

In many cases the movement against the normal direction of traffic originates at an interlocking plant where there will be two ramps R and R¹ on each side of the track, there being two ramps at such a place in order that the emergency brakes may be applied at such a point if necessary on a train approaching this point in the normal direction of traffic. To permit a train making a reverse movement against the normal direction of traffic to pass these two ramps it is necessary to supply medium voltage to the righthand ramp R so that when the shoe S 80 engages this ramp and is swung to the right, the partial Circuit Number Twelve including the primary of the transformer TE, is established, thereby permitting the medium voltage on the ramp R to maintain the stop 85 relay E energized through means of the relay 38 and Circuit Number Eleven.

When a train making a movement against the normal direction of traffic passes the two ramps at an interlocking plant, the ramp 100 corresponding to the ramp R¹, and which is on the lefthand side of the track as regards the normal direction of traffic but is on the righthand side as regards the direction of movement of the train, is preferably 105 supplied with high or medium voltage to permit the train to proceed without being under dominance of the speed control apparatus SC.

The no-signal relay N is automatically 110 energized when a train making a reverse movement against the normal direction of traffic passes a ramp R on the righthand side, and when the other shoe S¹ is in its normal position, since under these conditions the 115 shoe S will be swung to the right as viewed in Fig. 1, and the contact finger 21 raised to close a circuit as follows:

Circuit Number Thirteen.

120 Commencing at the battery F, conductors 40, 41, 42, 102 and 103, winding 100 of the relay N, conductors 104 and 105, contact finger 21 in its upper closed position, conductor 106, contact finger 17¹ in its lower closed position, conductors 108, 107, 50 and 51 back to the battery F.

125 It should be noted that the no-signal relay N is ordinarily energized when a train commences a reverse movement against 130

traffic at a point where two ramps R and R¹ are located, since for reasons more fully explained hereinafter, the shoe S, then the lefthand shoe will be in engagement with the ramp R after the shoe S¹, then the righthand shoe, has left engagement with the ramp R¹, so that the Circuit Number Thirteen may be established.

In case the vehicle, when making a reverse movement of the character above described, is headed in the other direction so that the shoes S and S¹ are reversed, a circuit for energizing the no-signal relay N is established when the shoe S¹ is moved to the left as viewed in Fig. 1 and the shoe S is in its normal position, said circuit being traced as follows:

Circuit Number Fourteen.

20 Commencing at the battery F, conductors 40, 41, 42, 102 and 103, winding 100 of the relay N, conductors 104 and 109, contact finger 17 in its lower closed position, conductor 110, contact finger 20¹ in its upper closed position, and conductors 111, 50 and 51 back to the battery F.

After the no-signal relay N has been initially energized it is maintained energized so long as the train continues its reverse movement against the normal direction of traffic by reason of a maintaining or stick circuit traced as follows:

Circuit Number Fifteen.

35 Commencing at the battery F, conductors 40, 41, 42, 102 and 112, winding 101 of the relay N, conductor 113, armature 114 of the relay N in its upper position, conductor 115, contact finger 16 in its lower closed position, conductor 116, contact finger 16¹ in its lower closed position and conductors 117, 50 and 51 back to the battery F.

It can be seen that the last traced circuit is unaffected by the successive engagement 45 of the shoe S with the ramps R when the train is moving in a direction opposite to the normal direction of traffic, but as soon as the train changes its direction of movement and moves in the direction of the arrow X, the first ramp R will rock the shoe S to the lift, as viewed in Fig. 1, thereby lifting the contact finger 16 to interrupt the maintaining or stick Circuit Number Fifteen and since neither the Circuits Numbers Thirteen and Fourteen are established 55 at this time, the no-signal relay 21 is deenergized. In this way the no-signal relay N is automatically energized as soon as a train commences a movement against the normal direction of traffic, and is also deenergized as soon as the train assumes its movement in the normal direction of traffic.

It should be noted that the maintaining 60 Circuit Number Fifteen is also interrupted 65 when the righthand shoe on a train traveling

in the direction opposite to the normal direction of traffic engages a ramp R¹ on the lefthand side of the track as regards normal direction of traffic, but on the same side of the track as the righthand shoe of the vehicle as regards the direction of movement of said vehicle. In other words, assuming the vehicle shown in Fig. 1 to be traveling in the direction opposite to that indicated by the arrow X, and that the shoe S¹ engages the ramp R¹; then the shoe S¹ will be rocked to the right, as viewed in Fig. 1, thereby raising the contact fingers 16¹ to interrupt the maintaining Circuit Number Fifteen for the no-signal relay. Since this particular condition just described can arise only when a train moving against the normal direction of traffic reaches a point where there are ramps on both sides of the track governed by an interlocking plant, it is possible very shortly thereafter to reenergize the no-signal relay by establishing the Circuit Number Thirteen in the same way as hereinbefore described.

When the no-signal relay N is energized its armature 121 in its upper position closes a circuit for energizing the no-signal device NS as follows:

Circuit Number Sixteen.

Commencing at the battery F, conductors 40, 41, 42, 43, 52 and 118, device NS, conductor 119, armature 121, in its upper position, and conductors 122, 58, 59 and 51 back to the battery F.

The controlling effects produced as hereinbefore described may be conveniently placed in a tabular form as below, it being understood that the terms right and left mean right and left with reference to the direction in which the vehicle or train is traveling at the time.

Shoe position.		Voltage on ramp.		Gives—
Left.	Right.	Left.	Right.	
Down..	Up..	-----	-----	Proceed indication.

plied to the ramps in accordance with traffic conditions will now be described. Referring to Fig. 2, a horizontal stretch of track divided into blocks A, B, C and D by insulating joints 123 is shown, and it is further assumed that this stretch of track is intersected near its righthand end by another stretch, it being understood that the control of trains over this other stretch of track is accomplished in a similar way to that about to be described for the first mentioned or horizontal stretch. The normal direction of traffic over the horizontal stretch is indicated by the arrow X. Associated with each block and located preferably at the entrance thereto are control ramps RB, RC and RD which correspond to the ramp R in Fig. 1; and associated with the block D at the entrance to which the absolute stop should be given, is a ramp RD¹, which corresponds to the lefthand ramp R¹ in Fig. 1. The trackway circuits are preferably supplied with alternating current derived from a suitable alternating current generator 124 connected to the line wires 125 and 126; and at the entrance to each block is located a transformer, the primary of which is connected across said line wires, said transformers being designated 25 127, 127¹ and 127² for the blocks B, C and D respectively. The parts associated with the blocks B, C and D are in many respects the same, and these parts which are the same, will be given like reference characters 30 having exponents added thereto. A portion 128 of the secondary of the transformer 127 is connected by conductors 129 and 130 across the track rails 1 and 2 at the exit end of the preceding block; and across the 35 track rails 1 and 2 at the entrance end to each block a track relay 133 of suitable construction is connected by conductors 131 and 132, said track relays having armatures 134 and 135 represented in accordance with established convention.

In addition to controlling the voltage supplied to the ramps RC, RD and RD¹ by the track relays of the adjacent blocks, it is necessary to control these voltages according to whether or not it is desired to bring a vehicle to an absolute stop at the end of the block C; and for this purpose a suitable circuit controlling device 150 having contact fingers or switches 151, 152 and 153 is provided, it being contemplated that this circuit controlling device 150 will be operated simultaneously or in connection with the usual fixed signal O at the entrance to the block D. In other words, the circuit controlling device 150 may be directly connected to the signal O and operated simultaneously with the movement of this signal, or said device may be operated in connection with the signal O by the lever or the

like, controlling said signal, this signal being controlled in any one of the usual ways. 65

To enable a clear understanding of the trackway circuits shown in Fig. 2, without entering into an unnecessarily detailed description, the circuits set up and the voltage supplied to each ramp under different traffic conditions will be briefly described, and by reference to the table hereinbefore given the effect produced by these voltages will be apparent. Assuming a train in the block A 70 about to enter the block B, then before the first pair of wheels and axle of this train actually enter the block B, the track relay 133 will be energized so that high voltage is applied to the ramp RB by a partial 75 circuit as follows: Commencing at the ramp RB, conductors 139, armature 134 of the track relay 133, in its upper position, conductor 140, secondary of the transformer 127 and conductor 136 of the track rail 1. When 80 the train in the block A actually enters the block B, the armature 134 of the track relay 133 drops and connects the ramp RB by conductor 139 and armature 134 in its lower position to a conductor 141 leading 85 ahead to the armature 135¹ of the track relay 133¹ of the block C, so that if the block C is not occupied by another train a medium voltage is supplied along conductor 142 to the ramp RB from a portion of the secondary of the transformer 127¹. However, 90 if the block C is occupied, the armature 135¹ will be in its lower position, thereby totally disconnecting the ramp RB from any source 95 of current, that is, there will be zero voltage 100 on the ramp RB. It will be apparent that, if the block B is occupied at the time a train approaches the entrance to this block, the armature 134 of the track relay 133 will be in its lower position, so that either a 105 medium or no-voltage will be supplied to the ramp RB depending upon whether or not the block C is occupied at that time. From the foregoing in connection with the 110 table and description of the operation of the parts shown in Fig. 1, it can be seen that a train in the block A approaching the block B may be allowed to proceed, be compelled to reduce its speed or may be required to enter the block B only under 115 such conditions and such a speed as may be desired and permitted by the particular construction of the speed control apparatus used, depending on whether or not the block B or C is occupied. 120

For the next condition of traffic to be considered, assume that the signal O has been put to stop manually by the operator in the tower, because the right of way has been given to another train on the track intersecting the block D, and under this condition the circuit controlling device 150 will be 125 in the position shown in Fig. 2. When a

train approaches the block C and the first contact shoe thereon engages the ramp RC, high voltage will be supplied to this ramp RC, providing the block C is not occupied at the time by a partial circuit as follows: Commencing at the ramp RC, conductor 143, armature 134¹ of the track relay 133¹ in its upper position, conductor 144, secondary of the transformer 127¹ and conductor 136¹. When the train actually enters the block C the armature 134¹ drops and connects the ramp RC through conductor 143, and said armature to the conductor 145, and since the switch 151 is assumed to be in the position shown in Fig. 2, no voltage will be supplied to the ramp RC. In this way, the speed control apparatus on a train can be set into operation at the time it enters the block C, regardless of traffic conditions in the next block in advance, that is, the block D. As the train progresses and the first contact shoe thereof engages the ramp RD, the speed control apparatus will continue to be effective, since the ramp RD is disconnected from any source of current by reason of the fact that the switch 153 is open; and, consequently, the train may pull up to the signal O at the limited speed and under the restriction imposed upon it by the speed control apparatus. In order to permit the vehicle to pull up to the signal O, and also to permit a contact shoe of said train to be on the ramp RD, for the reason hereinafter pointed out, the ramp RD¹ is so located that the first lefthand shoe does not engage this ramp until after the righthand shoe has engaged the ramp RD. If the train attempts to pass the signal O, however, the lefthand shoe will engage the lefthand ramp RD¹, which has no voltage applied thereto, because the switch 152 is open; and, consequently, all of the conditions necessary for the emergency application of the brakes are present; that is, the control relay K is deenergized, both a righthand and a lefthand shoe are swung rearwardly, and there is no voltage on the lefthand ramp. After traffic has cleared and the signal O and the circuit controlling device are placed in position to permit the train to proceed, high voltage will be applied to the ramp RD, providing the block D is not occupied, and this high voltage will energize the control relay K and restore the parts of the speed control apparatus to their idle position, since the ramps RD and RD¹ are so located that when the train pulls up to the signal O, the first right hand shoe of the train is on the ramp RD. Also, the ramp RD¹ is made shorter than the ramp RD, so that the right hand shoe of a train moving in the normal direction of traffic indicated by the arrow X will be on the ramp RD after the left hand shoe of this train has left engagement with

the ramp RD¹, this relative length and location of the ramps RD and RD¹ being necessary to prevent the energization of the no-signal relay N when a train passes an interlocked signal when traveling in the normal direction of traffic.

In order to permit a train to pass along the horizontal stretch of track subject only to the control of its speed control apparatus, it is only necessary to shift the circuit controlling device 150 to close the switches operated thereby, whereupon the conductor 145 associated with the ramp RC is connected by conductor 146 to the armature 135² of the track relay 133² so as to make in effect the same type of controlling circuit as associated with the ramp RB. The closing of the switch 152 connects the left hand ramp RD¹ by means of conductors 137 and 154 to the medium voltage tap of the secondary of the transformer 127², so that a medium voltage is found on the ramp RD for all trains passing that ramp. When the switch 153 is closed the ramp RD is connected by conductors 138 and 148 to the armature 134², so as to form in effect the same type of controlling circuit as shown in connection with the ramp RB. In this way, by closing the switches 151, 152 and 153 the controlling circuits for the ramps RC and RD are made the same as for the ramp RB. It should be understood that the particular arrangement of trackway circuits shown in Fig. 2 is merely illustrative and does not exhaust the possible combinations and modifications susceptible of use with this invention.

While the controlling devices and the controlling circuits therefor have been designed in the particular embodiment of the invention shown and described so as to be operated by alternating current, it is apparent that simple modifications, which will be obvious to those skilled in the art of railway signaling, may be made whereby direct current or some other current may be used as the operating medium. Also, it should be understood that the invention is in no wise limited to a particular kind of speed control apparatus, nor to a particular means for obtaining an absolute stop; likewise, the satisfactory operation of the system is not dependent necessarily upon the use of contact shoes and contact rails since inductive devices capable of performing the same functions might be used. Other modifications and changes may be made in the particular construction of parts and arrangements of the controlling circuits therefor shown and described, without departing from the invention and without modifying or changing the functions of these parts or their operation, and also various features may be combined with the system as shown and described without departing from the invention, as for example, several locomo-

tives or motor cars each equipped with the system may be included in the same train.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States, is:

1. In a system for automatically protecting railway traffic, in combination: a track; a vehicle adapted to travel over said track; a device carried by said vehicle on each side thereof and capable of moving relatively to said vehicle in either of two directions; automatic train control apparatus on the vehicle; a normally closed circuit for maintaining said apparatus in its idle condition; means controlled by each device for interrupting said circuit when that device is moved in one direction relatively to the vehicle; normally open partial circuits for preventing the operation of said apparatus independently of said normally closed circuit; means operated by the movement of either device in said one direction for connecting that device to the corresponding partial circuit; and traffic controlled means along the track for actuating said devices and for supplying current to said partial circuits.

2. In a system for automatically protecting railway traffic, in combination: a track; a vehicle adapted to travel over said track; automatic train control apparatus on the vehicle; a partial circuit for controlling said apparatus; a device on the vehicle on each side thereof and capable of moving relatively to said vehicle in either of two directions; means governed by each device for electrically connecting it to a terminal of said partial circuit when that device is moved in one direction relatively to the vehicle; and means along the track for actuating one or the other of said devices in said last mentioned direction when the vehicle is traveling over the track in the normal direction of traffic, depending upon which end of the vehicle is ahead.

3. In a system for automatically protecting railway traffic, in combination: a track; a vehicle adapted to travel over said track; braking means for retarding the movement of the vehicle; a relay for controlling said braking means; a circuit for normally maintaining said relay energized; a partial circuit for governing said relay; devices carried by the vehicle on the opposite sides thereof and each capable of moving relatively thereto in either of two directions; means controlled by said devices for interrupting said first mentioned circuit when both of said devices are moved in either direction rela-

tively to the vehicle; means governed by each device for electrically connecting that device to a terminal of said partial circuit when that device is moved in one direction relatively to the vehicle; and means along the track for governing the movement of said devices.

4. In a system for automatically protecting railway traffic, in combination: a track; a vehicle adapted to travel over said track; braking means for retarding the movement of said vehicle; a multiple circuit for controlling said braking means, said braking means being set into operation when both of said circuits are interrupted; a relay for controlling each of said circuits; two impulse receiving elements carried by the vehicle on opposite sides thereof; means governed by either impulse element for controlling one relay; and means responsive to the simultaneous and joint influence of both impulse elements for controlling the other relay.

5. In a system for automatically protecting railway traffic, in combination: a track; a vehicle adapted to travel over said track; a distinctive signal; and means on the vehicle and located along the track in cooperative relation for automatically operating said signal when and as long as the vehicle travels over said track in the direction opposite to the normal direction of traffic.

6. In a system for automatically protecting railway traffic, in combination: a vehicle; apparatus for governing the speed of said vehicle; mechanism for stopping said vehicle; partial circuits for separately controlling said apparatus and said mechanism; a device carried by the vehicle and capable of movement relatively thereto in either of two directions; means governed by said device for connecting it to a terminal of one or the other of said partial circuits according to the direction of movement of said device; and means along the track for moving said device selectively in one direction or the other.

7. In an automatic train control system, in combination: a vehicle; an automatic train control apparatus on the vehicle; a contact shoe carried by the vehicle and comprising a movable element; a partial circuit on the vehicle controlling said apparatus; and normally open circuit controlling means for connecting said partial circuit to said shoe, said means being operated to establish such connection when said element is moved in one direction but not in the other direction by cooperating devices along the track for the vehicle.

8. In an automatic train control system for a railroad, speed control apparatus wholly on a vehicle and having its operation conditioned from the trackway, said apparatus while operating acting to

enforce predetermined speed restrictions for the vehicle, automatic stop mechanism on the vehicle for arresting the movement thereof independently of its speed, means 5 normally acting to prevent operation of the stop mechanism and rendered inactive when the speed control apparatus is set into operation, and impulse transmitting means comprising trackway devices and separate elements 10 on the vehicle acting when co-operating separately or jointly to produce distinctive controls for governing the speed control apparatus and the stop mechanism at permissive and absolute control points 15 along the track.

9. In an automatic train control system, in combination: a vehicle; speed control apparatus on the vehicle for gradually controlling the movement thereof; automatic 20 stop mechanism on the vehicle for immediately arresting the movement thereof; partial circuits for controlling said apparatus and said mechanism; a contact shoe carried by the vehicle and comprising a movable element; and normally open circuit controlling 25 means for selectively connecting said contact shoe to said partial circuits when said element is moved in opposite directions, by devices along the track for the vehicle.

30 10. In an automatic train control system, in combination: a vehicle; apparatus for gradually controlling the movement of the vehicle; mechanism for bringing the vehicle to an absolute stop; duplicate impulse devices on opposite sides of the vehicle effective 35 when either is influenced separately to control said apparatus and when influenced jointly to control said mechanism; and means for preventing the operation of said mechanism while said apparatus is in its non-controlling condition.

11. In an automatic train control system, in combination: a vehicle; separate speed controlling apparatus and automatic stop 45 mechanism on the vehicle; separate relays for controlling said apparatus and said mechanism; partial circuits for controlling said relays; contact shoes carried by the vehicle on opposite sides thereof; ramps 50 along the track for giving to the contact shoe on the corresponding side of the vehicle a predetermined movement relative to the vehicle when the vehicle travels in the normal direction of traffic; a ramp along the track for giving to the contact shoe on the other side of the vehicle a different movement 55 relatively to the vehicle when the vehicle travels in the normal direction of traffic; and circuit controlling means associated with each shoe and operated by the movements thereof to selectively connect that shoe to one or the other of said partial circuits.

60 12. In an automatic train control system, in combination: a vehicle and a track there- 65

for; a shoe carried by the vehicle on each side thereof, each shoe comprising an element which is moved by the cooperation of the shoe with a ramp along the track in a direction relatively to the vehicle according 70 to which side of the track the ramp is located and also according to the direction of movement of the vehicle relative to that ramp; separate automatic speed control apparatus and stop mechanism on the vehicle selectively controlled by a particular movement of the element of either shoe and by the simultaneous movement of the shoes in either direction; ramps located at intervals 75 along one side of the track for causing said 80 particular movement of the element of the shoe on that side of the vehicle to control the speed control apparatus; and ramps on both sides of the track at certain points for causing movement of the elements of both 85 shoes and thereby controlling the stop mechanism.

13. In an automatic train control system, in combination: a railroad track having a control point where trains may be allowed 90 to proceed according to traffic conditions at some times and should be brought to an absolute stop regardless of traffic conditions at other times; impulse transmitting means at said control point; other impulse transmitting means at a distance in the rear of the control point; trackway circuits for governing the controlling condition of both of said impulse transmitting means in accordance 95 with traffic conditions; and manually operable means for placing both impulse transmitting means into a train retarding condition independently of said trackway circuits.

100 14. In an automatic train control system, in combination: a vehicle; automatic stop mechanism for bringing the vehicle to an immediate stop; impulse transmitting means comprising trackway devices and two separate elements on the vehicle; means tending 105 to cause operation of said mechanism when both of said elements cooperate with corresponding trackway devices; means dependent upon the controlling condition of one of 110 said two trackway devices for preventing operation of said mechanism; and manually operable means for governing the controlling condition of said one trackway device.

115 15. In an automatic train control system, in combination: a vehicle and a track there- 120 for; speed control apparatus on the vehicle for gradually controlling the movement thereof; automatic stop mechanism on the vehicle for immediately arresting the movement thereof; trackway devices and elements on the vehicle arranged in cooperative 125 relation and constituting means for transmitting impulses from the track to the vehicle; said trackway devices being arranged in a predetermined way at stopping points 130

and in a different way at speed control points; trackway circuits for automatically controlling said trackway devices at speed control points in accordance with traffic conditions; and manually operable means for governing the trackway devices at the stopping point and for simultaneously governing the trackway device at the speed control point next in the rear of said stopping point, whereby upon its approach to a stopping point the movement of the vehicle will be first gradually regulated and then immediately arrested if the vehicle continues past the stopping point.

15 16. In an automatic train control system, in combination: a vehicle and a track therefor; speed control apparatus on the vehicle for gradually regulating the movement thereof; automatic stop mechanism on the 20 vehicle for immediately arresting the movement thereof; circuits and apparatus partly on the vehicle and partly along the track for automatically controlling the speed control apparatus in accordance with traffic conditions; and manually operable means for controlling said circuits and apparatus independently of traffic conditions to cause operation of the speed control apparatus and a subsequent operation of the automatic stop mechanism as the vehicle approaches and passes a stopping point along the track.

17. In an automatic train control system, in combination: a vehicle and a track therefor divided into track circuit blocks; impulse devices located at intervals along the track to control the movement of trains through the several blocks; trackway circuits controlled by the track circuits of said blocks for governing the controlling conditions of said impulse devices in accordance with traffic conditions; elements on the vehicle adapted to alternately cooperate with said impulse devices according to the way in which the vehicle is headed; an additional impulse device located at a point along the track where the vehicle should be brought to an absolute stop, said additional impulse device being arranged to cooperate with the element on the vehicle which is not in position to cooperate with the first mentioned impulse devices; automatic stop mechanism on the vehicle having its operation responsive to the controlling condition of the additional impulse device; automatic speed control mechanism on the vehicle having its operation responsive to the controlling conditions of the other impulse devices; and manually operable means for governing the controlling condition of said additional impulse device.

18. In an automatic train control system, in combination: a railroad track having an automatic block signal territory for permissive stops and a point of absolute stop; ramps located at intervals along one side of the

track throughout the block signal territory for controlling the movement of trains through said blocks; trackway circuits for governing the controlling condition of said ramps in accordance with traffic conditions in 70 said blocks; two ramps located opposite one another on opposite side of the track at the point of absolute stop; and manually operable means for governing the controlling condition of said two ramps and also the 75 controlling condition of the ramp next in the rear thereof independently of said trackway circuits.

19. In an automatic train control system, in combination: a railroad track having a 80 region where trains may be governed in accordance with traffic conditions at some times and be slowed down and brought to an absolute stop at other times; impulse devices and trackway circuits for governing 85 the movement of trains through said region in accordance with traffic conditions; and manually operable means for governing said trackway circuits independently of traffic conditions to cause trains to be slowed down 90 and brought to an absolute stop.

20. In an automatic train control system, in combination: a vehicle; impulse transmitting means comprising devices along 95 the track cooperating with elements on the vehicle; said elements being responsive to the direction of movement of the vehicle relative to the trackway devices; a normally inactive distinctive signal; means controlled by said elements for rendering said signal active when the vehicle travels opposite to the normal direction of traffic; a circuit acting to maintain said signal active after it has been initially rendered active; and means controlled by said elements when the vehicle travels in the normal direction of traffic for controlling said circuit to cause said signal to automatically resume its normal inactive condition.

21. In an automatic train control system, in combination: a vehicle and a track therefor; impulse transmitting devices located at intervals along the track; impulse receiving elements on the vehicle adapted to cooperate with said trackway devices, said elements comprising a movable member which is moved in opposite directions according to the direction of movement of the vehicle relative to a trackway device; automatic train control apparatus governed by the movement of said member in one direction, this movement corresponding to the movement which is given said member when the vehicle travels in the normal direction of traffic; and a distinctive signal rendered active by the movement of said member in an opposite direction for indicating that the vehicle is travelling opposite to the normal direction of traffic.

22. In an automatic train control system,

in combination: a vehicle; automatic train control apparatus on the vehicle; a relay for controlling said apparatus; a normally closed stick circuit for maintaining said relay energized; a partial circuit for causing energization of the relay independently of its stick circuit; a contact shoe carried by the vehicle and comprising a movable element; ramps along the track adapted to cooperate with said shoe and cause movement of its element in accordance with the direction of movement of the vehicle; and circuit controlling means operated by the movement of said element when the vehicle is traveling in the normal direction of traffic for simultaneously breaking said stick circuit and connecting said partial circuit to the shoe.

23. In an automatic train control system, in combination: a vehicle; separate speed control apparatus and automatic stop mechanism on the vehicle; separate partial circuits for controlling said apparatus and said mechanism; a contact shoe carried by the vehicle and comprising a movable element; ramps along the track for cooperating with said shoe and for causing movement of the element thereof in accordance with the direction of movement of the vehicle relative to the ramp; and circuit controlling means operated by the movement of said shoe for simultaneously connecting it to said separate partial circuits.

24. In an automatic train control system, in combination: a vehicle and a track therefor; impulse receiving means on the vehicle comprising two separate elements arranged on opposite sides thereof; permissive impulse transmitting means along the track; one or the other of said elements on the vehicle being active to cooperate with said permissive impulse transmitting means when the vehicle is traveling in the normal direction of traffic according to the way in which the vehicle is headed; absolute impulse transmitting means located at predetermined points along the track; the one of said elements which is inactive when the vehicle is headed in a given direction being in position to cooperate with the absolute impulse transmitting means.

25. In an automatic train control system, in combination; a vehicle; a transformer on the vehicle having one terminal of its primary connected to the wheels of the vehicle; contact shoes carried by the vehicle on opposite sides thereof and each comprising a movable element; ramps along the track for giving to the elements of one or the other of said contact shoes a predetermined movement when the vehicle travels in the normal direction of traffic; and normally open circuit controlling means associated with each shoe and operated by said predetermined movement of its element for connecting that shoe to the other terminal

of the primary of said transformer; and train control apparatus on the vehicle responsive to the flow of current in the primary of said transformer.

26. In an automatic train control system for railroads which have block signal territory where permissive control may be enforced, and one or more control points in interlocking territory where absolute control should be enforced; in combination: trackway impulse devices along one side of the track throughout block signal territory and controlled in accordance with traffic conditions; a vehicle; impulse receiving elements carried by the vehicle on opposite sides thereof and adapted to cooperate separately with said trackway devices according to which end of the vehicle is ahead; permissive control apparatus on the vehicle controlled by the impulse element which is on the side of the vehicle corresponding with said trackway devices; other similar trackway impulse devices located on opposite sides of the track at each control point of absolute control so as to cooperate with both of the vehicle carried impulse elements; manually operable interlocked means for governing the controlling condition of said other trackway devices to cause them to enforce either absolute control or permissive control, said means acting to place the next trackway device at braking distance in the rear of the control point in its permissive controlling condition whenever absolute controlling conditions are set up; and absolute control mechanism on the vehicle having its operation influenced by the oppositely located trackway devices at said control points, whereby permissive control of the vehicle in accordance with traffic conditions is always obtained in the block signal territory, and at some times past the absolute control points, while at other times permissive control followed by absolute control is obtained as the vehicle approaches and passes said absolute control points.

27. In an automatic train control system for railroads which have automatic block signal territory where permissive control may be enforced and absolute control points in interlocking territory where absolute control of the vehicles should occur, the combination with a vehicle; of separate impulse receiving elements carried thereby; trackway impulse devices arranged in one way in block signal territory, and in a different way at each absolute control point, so as to influence the impulse receiving elements on the vehicle differently; means for causing the controlling condition of the trackway devices in block signal territory to be governed automatically in accordance with traffic conditions; manually controlled means for regulating the controlling con-

- dition of the trackway devices at the absolute control points; and separate permissive control and absolute control apparatus on the vehicle controlled selectively by the 5 different influence produced on the vehicle carried elements by the different arrangements of trackway devices.
28. In an automatic train control system for railways, the combination with a vehicle, 10 of automatic train control means therefor including absolute control mechanism and permissive control apparatus, impulse transmitting means for governing the operation of the permissive control apparatus and 15 comprising traffic controlled trackway devices and duplicate vehicle carried elements, said vehicle carried elements being separately influenced by the trackway devices according to which end of the vehicle is 20 ahead while it is traveling in the normal direction of traffic, and manually controlled means including the same vehicle carried elements and similar additional trackway devices for causing operation of the absolute 25 control mechanism at certain points along the track.
29. In an automatic train control system for railroads, the combination with a vehicle, 30 of automatic train control means on the vehicle including speed control apparatus adapted when set into operation to restrict continued progress of the vehicle to a pre-determined minimum speed, and absolute stop mechanism adapted to apply the brakes 35 to the vehicle regardless of its speed; duplicate impulse receiving elements on the vehicle each separately effective to control the operation of the speed control apparatus, and jointly effective to control the operation 40 of the stop mechanism; and trackway devices for influencing the vehicle carried elements separately or jointly at different control points along the track.
30. In an automatic train control system 45 for railroads, the combination with a vehicle, of automatic train control means therefor adapted to enforce permissive control by regulating its speed or absolute control by applying its brakes regardless of its 50 speed; trackway impulse devices along the track, some arranged on the same, and some on opposite sides of the track; receiving elements carried by the vehicle on opposite sides thereof and adapted to cooperate with 55 a trackway device on the corresponding side of the track, thereby transferring controlling influences from the trackway to the vehicle; and control means on the vehicle for causing its automatic train control means to 60 be governed in one way by trackway devices on one side of the track as regards the direction of movement of the vehicle, in a different way by trackway devices on the opposite side of the track, and in a still dif- 65 ferent way by trackway devices on both sides of the track, whereby the same receiving elements on the vehicle are made effective by different arrangements of trackway impulse devices to enforce either permissive or absolute control while the vehicle 70 is traveling in the normal direction of traffic, and also permit the vehicle to travel opposite to the normal direction of traffic without being stopped.
31. In an automatic train control system 75 for railroads, the combination with a vehicle, of automatic train control means therefor adapted to enforce either permissive control by regulating the speed of the vehicle or absolute control by applying the 80 brakes regardless of speed, impulse receiving elements on the vehicle adapted to be influenced by trackway circuits and devices in different ways to enforce either the permissive or the absolute control, trackway devices for cooperating with said impulse receiving elements, and arranged differently at the various control points along the track to produce the permissive control or 85 absolute control required, means for controlling the trackway devices at permissive control points in accordance with traffic conditions in advance, and manually operable means for governing the devices at absolute control points according to transient 90 dangerous conditions.
32. An automatic train control system for railroads capable of regulating the speed of vehicles so as to enforce permissive control, or apply the brakes on the vehicles regardless of speed so as to enforce absolute control, or permitting the vehicles to proceed opposite to the normal direction of traffic without being stopped, said system comprising, in combination: impulse devices 100 along the track adapted to communicate controlling influences to each passing vehicle; separate permissive and absolute train control apparatus carried by each vehicle; and impulse receiving elements on the vehicle for controlling said apparatus selectively, said receiving elements being influenced differently by different arrangements 105 of trackway devices, and also differently by the same arrangement according to the direction of movement of the vehicle thereby.
33. In an automatic train control system 110 for railroads, the combination with a vehicle; of automatic train control means therefor; impulse receiving elements carried by the vehicle on both sides thereof near opposite ends; impulse devices along the track, some of said impulse devices at certain control points being arranged to cooperate separately with the corresponding vehicle carried element, and others at different control points being arranged to cooperate simultaneously in pairs with both of said elements;

and control means on the vehicle influenced by the cooperation of the vehicle carried elements with the trackway devices for governing said train control means in different ways depending upon whether one or both of said elements are influenced.

34. In an automatic train control system for railroads, in combination: a vehicle; speed control apparatus on the vehicle; stop mechanism on the vehicle for applying the brakes thereof regardless of the speed; impulse receiving elements carried by the vehicle on both sides thereof; impulse devices along the track, some arranged on one side of the track to cooperate separately with the corresponding receiving elements, and others at certain absolute control points arranged to cooperate simultaneously with both of the receiving elements; control means on the vehicle influenced by the cooperation of said vehicle carried elements with the trackway devices and adapted to control the speed control apparatus when said elements are influenced separately, and the stop mechanism when said elements are influenced simultaneously; and means for preventing operation of the stop mechanism unless the speed control apparatus is acting.

35. In an automatic train control system for railroads, the combination with a vehicle, of automatic train control means therefor adapted to enforce either permissive control by regulating the speed of the vehicle, or absolute control by applying the brakes regardless of speed; duplicate trackway devices at control points along the track in interlocking territory where either permissive or absolute control should be enforced; manually controlled means for selectively placing said trackway devices under the control of traffic conditions in advance, or in condition to exert absolute control on a passing vehicle irrespective of traffic conditions; and control means on the vehicle responsive to the influence of said trackway devices in their different controlling conditions for governing the train control means on the vehicle accordingly.

36. In an automatic train control system for railroads having a region where trains may be governed in accordance with traffic conditions at some times and should be slowed down and brought to an absolute stop at other times, in combination: impulse devices located on opposite sides of the track at the point of absolute stop; another impulse device at braking distance in the rear of said first mentioned device; trackway circuits for governing the controlling conditions of all of said devices in accordance with traffic conditions in advance thereof; and manually controlled means for modifying the controlling condition of said impulse devices independently of said trackway cir-

cuits, thereby causing the vehicle to be slowed down and then stopped as it approaches and passes the point of absolute stop.

37. In an automatic train control system for railroads, the combination with a vehicle, of automatic train control means therefor including speed control apparatus adapted to restrict continued progress of the vehicle to a predetermined minimum speed, absolute stop mechanism adapted to apply the brakes to the vehicle regardless of its speed, and a normally inactive distinctive signal for indicating that the vehicle is proceeding without the protection of its train control means; duplicate impulse receiving elements on the vehicle disposed on opposite sides thereof; trackway impulse devices along the track arranged to influence the vehicle carried elements separately at some points, and simultaneously at others; means acting when the vehicle carried elements are influenced separately for controlling the operation of the speed control apparatus and the distinctive signal alternatively, depending upon the direction of movement of the vehicle over the track; and means acting when the vehicle carried elements are influenced jointly for controlling the operation of the stop mechanism; whereby the same elements on the vehicle are made effective by different arrangements of trackway devices to control the speed control apparatus, the distinctive signal, and the stop mechanism.

38. In an automatic train control system for railroads, in combination: a vehicle; automatic train control apparatus on the vehicle; a distinctive signal for indicating that the vehicle is traveling without the protection of its train control apparatus; impulse transmitting means comprising impulse receiving elements on the vehicle arranged to cooperate with traffic controlled impulse devices along the track, said receiving elements on the vehicle being influenced in one way by the trackway devices while the vehicle is traveling in the normal direction of traffic regardless of which end of the vehicle is ahead, and in a different way when the vehicle travels opposite to the normal direction of traffic; and means responding to the different ways in which said receiving elements are influenced for governing said apparatus and signal selectively, whereby the alternative use of the train control apparatus and distinctive signal are automatically determined according to the direction of movement of the vehicle.

39. In an automatic train control system for railroads, in combination: a railroad track; impulse devices disposed along the righthand side of the track as regards the normal direction of traffic at certain control points, and on both sides of the track in over-

lapping staggered relation at other control points; a vehicle; impulse receiving elements carried by the vehicle on opposite sides thereof; a relay on the vehicle; control means responsive to the cooperation of said elements with corresponding trackway devices for governing said relay, said control means acting to energize the relay when a receiving element on the lefthand side of the vehicle as regards its direction of movement cooperates with a trackway device and the righthand element is not affected, said control means also acting to maintain the relay energized until a righthand receiving element cooperates with a corresponding trackway device, whereby the relay will be energized whenever the vehicle travels opposite to the normal direction of traffic and will be maintained energized until the vehicle again travels in the normal direction of traffic.

40. In an automatic train control system for railroads divided into blocks each provided with a normally closed track circuit, impulse devices along the track some on one side and some on the other side of the center line of the track and at the same distance therefrom, means controlled by the track circuits for governing the controlling condition of the impulse devices on one side of the track to conform with traffic conditions in advance, manually controlled means for governing the impulse devices on the other side of the track, and automatic train control equipment on a vehicle influenced distinctively by said impulse devices depending upon their location.

41. In an automatic train control system, in combination: a railroad track; impulse devices located at intervals along one side of the track; a vehicle; a distinctive signal on the vehicle; impulse receiving elements carried by the vehicle on opposite sides thereof and adapted to cooperate separately with the trackway devices according to which end of the vehicle is ahead; and means controlled by either receiving element on the vehicle for causing operation of the distinctive signal when the vehicle travels over the track in one direction opposite to the normal direction of traffic.

42. In an automatic train control system for railroads having a point of absolute control, stopping means partly on the vehicle and partly along the track at said point of absolute control adapted to be controlled manually and operable to immediately arrest the movement of the vehicle, a trackway impulse device located at braking distance in the rear of said absolute control point, speed control apparatus on the vehicle adapted to be governed by said device, and trackway circuits and control means therefor acting to give a proceed or cautionary controlling

condition of said impulse device depending upon traffic conditions in advance, said trackway circuits being automatically changed to give cautionary control when said stopping means is made active.

43. In an automatic train control system for railroads having tracks divided into blocks each having a normally closed track circuit, impulse devices located at intervals along the track at one side of the center line thereof and controlled by certain track circuits in advance, impulse receiving elements on opposite sides of the vehicle which are responsive to the direction of movement of the vehicle with respect to a trackway device, train control means on the vehicle adapted to be controlled by the impulse receiving elements on either side of the vehicle when the respective element moves in one direction with respect to a trackway device and not in the other direction, whereby the vehicle will be controlled when traveling in the normal direction of traffic and not when moving against traffic, irrespective of which end of the vehicle is ahead; impulse devices on both sides of the track at predetermined stopping points, and means for stopping the vehicle when both of the elements thereon are simultaneously influenced.

44. In an automatic train control system, automatic stop mechanism on a vehicle for arresting the movement thereof regardless of its speed, a normally energized stick relay controlling said mechanism, two separate impulse devices on opposite sides of the vehicle adapted when influenced simultaneously to interrupt the stick circuit of said relay, and an independent energizing circuit for said relay controlled by one or the other of said impulse devices depending on which way the vehicle is headed.

45. In an automatic train control system, electrically controlled brake mechanism on a vehicle adapted to arrest the movement thereof independently of its speed, a normally closed circuit for maintaining said brake mechanism inactive, separate impulse devices on the vehicle adapted when influenced simultaneously to interrupt said circuit, and another circuit for independently maintaining said mechanism inactive and controlled by one of said devices.

46. In an automatic train control system for railroads having permissive and absolute control points, train control means on the vehicle including permissive control apparatus and absolute stop mechanism, separate impulse receiving elements on the vehicle, trackway impulse means arranged to influence one of the vehicle-carried elements at permissive control points and both at absolute control points, said vehicle-carried elements when thus influenced separately or jointly acting to control selectively the per-

missive control apparatus or the absolute stop mechanism, means including track circuits for normally governing said trackway means, and manually operable means for independently governing said trackway means at absolute control points.

47. In an automatic train control system for railroads having a control point in interlocking territory where trains should be brought to an absolute stop, impulse transmitting means adapted to exert controlling influences on passing trains at braking distance in the rear of said control point, trackway circuits for governing the controlling condition of said means in accordance with traffic conditions, means effective to prevent movement of trains by the absolute control point, and manually operable means for controlling said last mentioned means and for placing said impulse transmitting means in a train retarding condition independently of traffic conditions.

48. In an automatic train control system for railroads having a control point in interlocking territory where trains should be brought to an absolute stop, train control apparatus on a vehicle, means partly on the vehicle and partly along the track adapted to cause operation of said apparatus at braking distance in the rear of said control point and to prevent movement of the vehicle past said control point regardless of its speed, and manually operable means for controlling said means.

49. In an automatic train control system for railroads having a control point in interlocking territory where trains should be brought to an absolute stop, automatic speed regulating apparatus on a vehicle, trackway means at braking distance in the rear of said control point and normally active to set the apparatus on the vehicle into operation, normally active means at said control point for preventing movement of the vehicle thereby regardless of its speed, and manually operable means for controlling both of said means.

50. In an automatic train control system for railroads having a normal direction of traffic, the combination with a vehicle equipped for automatic control of its movement, of a distinctive signal thereon indicating that it is running without the protection of its automatic train control equipment, a stick relay controlling said signal, and means for energizing and deenergizing said relay automatically as the vehicle runs with or against traffic.

51. In an automatic train control system for railroads having a normal direction of traffic, the combination with a vehicle, of a normally deenergized stick relay thereon, and means partly on the vehicle and partly along the track for deenergizing and ener-

gizing said relay as the vehicle travels with and against the normal direction of traffic respectively.

52. In an automatic train control system for railroads having a normal direction of traffic, the combination with a vehicle, of a normally deenergized stick relay thereon, impulse elements on the vehicle cooperating with trackway means and effective to break the stick circuit of said relay when the vehicle travels in the normal direction of traffic.

53. In an automatic train control system for railroads having a normal direction of traffic, the combination with a vehicle, of a normally deenergized stick relay thereon, trackway means at one side of the center line of the track, and impulse devices carried by the vehicle on opposite sides thereof and each acting when influenced by the movement of the vehicle in the normal direction of traffic with respect to a trackway means to interrupt the stick circuit for said relay.

54. In a train control system for railroads having a normal direction of traffic, a vehicle having a distinctive signal thereon and a circuit for controlling said signal, an impulse element on the vehicle, and trackway devices for influencing said element, said element controlling said circuit when moved in a predetermined direction with respect to a trackway device, whereby the distinctive signal is automatically controlled as the vehicle travels with or against traffic.

55. In a train control system for railroads having a normal direction of traffic, a vehicle having a train control apparatus and a distinctive signal thereon, impulse elements on opposite sides of the vehicle, trackway means along one side of the center line of the track, the cooperation of either impulse element when on one side of the vehicle with respect to its direction of movement acting to control said apparatus and when on the other side to control said signal.

56. In an automatic train control system, train control apparatus on a vehicle, means partly on the vehicle and partly along the track for governing said apparatus in accordance with traffic conditions while the vehicle is traveling in the normal direction of traffic but not when running against traffic, and a stick relay on the vehicle also controlled by said means and deenergized and energized automatically as the vehicle runs with or against traffic.

57. In an automatic train control system, train control apparatus on a vehicle, means including duplicate devices on opposite sides of the vehicle and cooperating trackway means for governing said apparatus in accordance with traffic conditions while the vehicle is running in the normal direction

of traffic and irrespective of which end of the vehicle is ahead, and a safety appliance automatically actuated by said means as the vehicle runs against traffic with either end 5 ahead.

58. In an automatic train control system for railroads having a normal direction of traffic, car equipment including brake control apparatus and a distinctive signal, two 10 impulse devices carried by the vehicle on opposite sides thereof, and trackway means disposed at one side of the center line of the track for influencing said vehicle-carried devices, said trackway means and vehicle-carried devices cooperating to govern said apparatus only when the vehicle is traveling in the normal direction of traffic and to actuate the distinctive signal when the vehicle runs against traffic, both irrespective of which end of the vehicle is ahead.

59. In an automatic train control system for railroads having a normal direction of traffic, car equipment including permissive 25 control apparatus, absolute stop mechanism, and a distinctive signal, similar impulse receiving elements carried by the vehicle on opposite sides thereof, and trackway means for influencing said vehicle-carried elements 30 simultaneously or separately depending upon the direction of movement of the vehicle and which end is ahead, thereby governing the permissive control apparatus, the absolute stop mechanism or the distinctive 35 signal accordingly.

60. In an automatic train control system, train control apparatus on a vehicle, a distinctive signal on the vehicle, duplicate devices on opposite sides of the vehicle, and trackway means for influencing said devices, the operation of either device when on one side of the vehicle with respect to its direction of movement acting to control said apparatus, and the operation of 45 either device when on the other side of the vehicle with respect to its direction of movement acting to control said signal.

61. In an automatic train control system, car equipment comprising two relays responsive only to alternating current, two 50 transformers having their secondaries connected separately to said relays, and impulse receiving means on opposite sides of the car for energizing the primaries of said 55 transformers separately.

62. In an automatic train control system, the combination with a vehicle, of two transformers thereon, impulse receiving elements carried by the vehicle on opposite 60 sides thereof and adapted to energize the primaries of said transformers separately, and automatic train control equipment on the vehicle governed by the secondaries of said transformers.

63. In an automatic train control system,

in combination: a contact shoe mounted to swing in either direction from a middle position in accordance with the direction of its movement with respect to the trackway; circuit controllers operated selectively by 70 the movements of said contact shoe; a train controlling circuit governed by one of said circuit controllers; a signal having a distinctive aspect; and a controlling circuit for said signal controlled by the other of 75 said circuit controllers.

64. An automatic train control system comprising a contact shoe mounted to swing in either direction from a middle position, circuit controllers operated selectively by 80 the movement of said contact shoe, a relay, an energizing circuit for said relay including one of said circuit controllers, a stick circuit for said relay including the other 85 of said circuit controllers, and a signal controlled by said relay.

65. In a combined control and signal mechanism for vehicles the combination with a vehicle having a current supply, of two contact shoes on the vehicle; a plurality of 90 shoe switches operated by each shoe; a signal control relay on the vehicle; a stop valve device also on the vehicle; circuits for normally maintaining said relay and device, connections between the contact shoes and the control relay to maintain the latter by current picked up from ramp rail, and connections between the vehicle current supply, an armature of the control relay and the 95 valve device for maintaining the valve device by the vehicle current while the control relay is energized.

66. In combination, a vehicle having two electrically operated devices to be operated according to track conditions, electrical 105 means adapted to change circuit connections to said devices, means for breaking circuit to said means at each of predetermined intervals in succession as the vehicle passes along a track, and additional independently-controlled means also operable at such intervals as the vehicle passes along a track, for establishing alternative circuit connections to the first named means according to 110 track conditions.

67. In a train control system, in combination with an interlocked signal, trackway means adjacent to the signal operable to prevent the movement of vehicles thereby irrespective of their speed, brake control apparatus on a vehicle, other trackway means braking distance in the rear of the signal and adapted when in the active stopping condition to influence said apparatus on the passing vehicle, and means for placing both of said trackway means in their active condition when the signal indicates stop.

68. In a train control system, in combination with an interlocked signal, trackway means adjacent to the signal operable to 120 125 130

5 prevent the movement of vehicles thereby irrespective of their speed, a brake control device on a vehicle, means partly on the vehicle and partly on the track and effective a distance in the rear of the signal for influencing the brake control device on the vehicle dependent upon its speed and location with respect to the signal, and means for placing both of said means in the active 10 condition when the signal indicates stop.

15 69. In a train control system, in combination with an interlocked signal, trackway means adjacent to the signal operable to prevent the movement of vehicles thereby irrespective of their speed, speed governed 20 brake control apparatus on the vehicle, means partly on the vehicle and partly on the track for rendering said apparatus active braking distance in the rear of the signal, and manually controllable means for governing the indication of the signal and both of said means.

25 70. In a train control system, in combination with an interlocked signal, trackway means adjacent to the signal operable to prevent the movement of vehicles thereby irrespective of their speed, brake control apparatus on a vehicle including a speed responsive device and permissive speed means, 30 and means partly on the vehicle and partly on the track for governing the permissive speed means on the vehicle independently of traffic conditions as the vehicle approaches said signal at stop.

35 71. In a train control system, in combination with an interlocked signal, trackway means adjacent to the signal operable to prevent the movement of vehicles thereby irrespective of their speed, brake control 40 apparatus on a vehicle having its operation dependent upon the speed of the vehicle and adapted when set into operation to continue in operation until restored and means partly on the vehicle and partly on the track for initiating and restoring said apparatus in accordance with traffic conditions during its movement by the signal, said means acting to initiate the operation of said apparatus a distance in the rear of the signal independently of traffic conditions when the signal indicates absolute stop.

45 72. In a train control system, the combination with an interlocked signal and track circuits adjacent thereto, trackway means at the signal and at a distance in the rear thereof and having its controlling condition governed by said track circuits, and means for removing the trackway means from its track circuit control and for placing it in the 50 active stopping condition.

55 73. In a train control system, the combination with an interlocked signal and track circuits adjacent thereto, brake control apparatus on a vehicle including a speed responsive device and permissive speed means

changeable to establish restricted speeds for the vehicle, means partly on the vehicle and partly on the track and governed by said track circuits for automatically controlling the permissive speed means, and manually controllable means for rendering said last mentioned means active independently of traffic conditions.

75 74. In a train control system, the combination with an interlocked signal, trackway means adapted to communicate controlling impulses to the passing vehicles braking distance in the rear of the signal, a control circuit for said means, and means for causing interruption of said control circuit when the signal indicates stop.

80 75. In a train control system, the combination with an interlocked signal and track circuits adjacent thereto, of trackway means for communicating controlling influences to passing vehicles at a distance in the rear of the signal, a circuit adapted when closed to put said trackway means in its clear condition, and means for placing said circuit under the control of said track circuits or for removing said control.

85 76. In a train control system, the combination with an interlocked signal and a track circuit in advance thereof, of trackway means for governing passing vehicles at a point in the rear of the signal and having its controlling condition at times dependent upon the condition of the track circuit and at other times independent of such condition.

90 77. In a train control system, the combination with an interlocked signal, trackway means effective at a point adjacent to the signal and also braking distance in the rear thereof, means for governing said trackway means in accordance with traffic conditions, and manually operable means for placing both of the trackway means in the active condition independently of traffic conditions.

95 78. A system for controlling train movements in interlocked territory having a control point where trains should be stopped regardless of speed comprising, brake control apparatus on a vehicle having a cycle of operation, traffic controlled means for initiating and restoring said apparatus as the vehicle approaches and passes said control point, a device at said control point controllable to prevent movement of a vehicle thereby regardless of speed, and means whereby said traffic controlled means is placed in the active vehicle retarding condition independently of traffic conditions when said device is controlled to enforce an absolute stop.

100 79. A system for governing train movement in interlocked territory comprising, in combination with a manually controlled interlocked signal, a stop device at the signal, adapted when in the active stopping condition to prevent movement of the vehicles

- past the signal regardless of speed, a vehicle, and means partly on the vehicle and partly on the track for applying the brakes of the vehicle unless it assumes successively lower speeds as it approaches the signal, said last mentioned means being in the active condition when the stop device is in the stopping condition.
80. A system for governing train movement in interlocked territory comprising, in combination with a manually controlled interlocked signal, of trackway means adjacent to the signal having its controlling condition governed by traffic conditions in advance of the signal at times, and at other times being in the stopping condition irrespective of traffic conditions, a vehicle, and means partly on the vehicle and partly on the track for regulating the speed of the vehicle during its approach to the signal, the governing condition of said last mentioned means corresponding with the condition of said trackway means.
81. Track equipment for governing train movements in interlocked territory having a manually controlled interlocked signal, comprising, trackway means adjacent to the signal for communicating influences to a passing vehicle and adapted to assume a distinctive absolute stop condition other trackway means effective a distance in the rear of the signal, and means for governing both said trackway means in accordance with traffic conditions in advance of the signal at times and independently of traffic conditions at other times.
82. Track equipment for governing train movements in interlocked territory having a manually controlled interlocked signal, comprising, trackway means adjacent to the signal, and similar trackway means a distance in the rear thereof, the trackway means at the signal being adapted to assume a distinctive absolute stopping condition, and manually controllable means for governing both of said trackway means.
83. A train control system for governing the movement of vehicles in interlocked territory comprising, in combination with speed control apparatus and absolute stop mechanism on a vehicle, of trackway means effective a distance in the rear of the signal for governing the operation of the speed control apparatus, other trackway means adjacent to the signal and having a controlling condition distinctive from that of the first mentioned trackway means for governing the absolute stop mechanism, and manually controllable means for governing both of said trackway means.
84. A train control system for governing train movements through interlocked territory by an absolute interlocked signal, comprising, track elements on opposite sides of the track adjacent to the signal, another track element a distance in the rear of the signal, and manually controllable means for governing the condition of said track elements.
85. A system for governing train movement through interlocked territory past an interlocked signal comprising, a track element at one side of the track near the signal, a track element on the opposite side of the track near the signal, means for controlling the first mentioned track element in accordance with traffic conditions at times and for governing this element and the additional element independently of traffic conditions at other times.
86. A system for governing train movement through interlocked territory past an interlocked signal comprising, track elements on opposite sides of the track adjacent to the signal, another track element a distance in the rear of the signal, and means for governing all of said elements to conform with the indication of the signal.
87. A system for governing train movement through interlocked territory past an interlocked signal comprising, in combination with car-carried apparatus including permissive control apparatus and absolute stop mechanism, track elements on opposite sides of the track adjacent to the signal for governing the stop mechanism, another track element a distance in the rear of the signal for governing the permissive control apparatus, and means for governing all of said elements in accordance with the indication of the signal.
88. In a train control system, track elements disposed singly at permissive control points and in pairs at absolute control points, and manually controllable means for governing the pairs of elements and the single element next in the rear thereof.
89. In a train control system, track elements, disposed singly at permissive control points and in pairs at absolute control points, manually controllable means for governing the pairs of elements and the single element next in the rear thereof, and car-carried permissive and absolute control means influenced separately by the single track elements and the pairs of track elements.
90. In a train control system for causing absolute control of vehicles with preliminary permissive control, comprising pairs of track elements for influencing absolute control, and single track elements for influencing permissive control, and automatic permissive and absolute brake control means on a vehicle influenced separately by the single elements and by the pairs of elements when the vehicle travels in the normal direction of traffic irrespective of which end the vehicle is ahead.
91. In a train control system, the com-

bination with permissive and absolute brake control mechanism on a vehicle, of trackway means including elements disposed differently at permissive and absolute control 5 points, for influencing the mechanism on the vehicle separately, said trackway means being effective only when the vehicle travels in the normal direction of traffic.

92. In a train control system, the combination with speed control apparatus on a vehicle adapted to permit continued progress of the vehicle at a restricted speed, and absolute stop mechanism operable to arrest the movement of the vehicle regard- 10 less of its speed, an interlocked signal, and manually controllable trackway means for influencing said apparatus and mechanism separately as the vehicle approaches and passes said signal.

93. A system for governing train movement in interlocked territory by an interlocked signal comprising, in combination with speed control apparatus on a vehicle permitting continued progress thereof at a 15 restricted speed, of trackway means for initiating the operation of said apparatus at a distance in the rear of the signal when it indicates absolute stop, similar trackway means adjacent to the signal for restoring 20 said apparatus dependent upon traffic conditions in advance when the signal does not indicate absolute stop, and additional trackway means adjacent to the signal and effective to arrest the movement of the vehicle 25 irrespective of its speed, said last mentioned means being governed in accordance with the indication of the signal.

94. In a train control system, the combination with an interlocked signal and a 40 track circuit in advance thereof, trackway means effective at a distance in the rear of the signal for communicating controlling influences to passing vehicles, a control circuit for said trackway means governed by 45 the track circuit and adapted when closed to cause the trackway means to assume a safety condition, and manually operable means for interrupting said control circuit when the signal is set to indicate absolute 50 stop.

95. In a train control system, the combination with an interlocked signal and a track circuit in advance thereof having a track relay, a track element located a distance in the rear of the signal, a control circuit for the track relay governed by a front contact of the track relay, and manually controllable means for independently governing the continuity of said control circuit.

96. In a train control system for governing the movement of vehicles in interlocked territory, the combination with an interlocked signal and a track circuit in advance thereof of having a track relay, trackway means

adjacent to the signal effective when active to arrest the movement of a vehicle irrespective of its speed, a control circuit adapted when closed to render said trackway means inactive, other trackway means effective a 70 distance in the rear of the signal and having a control circuit governed by said track circuit, and manually controllable means for governing said control circuits.

97. In a train control system, the combination with an interlocked signal, brake control apparatus on a vehicle including changeable permissive speed means, and means for causing a change of the permissive speed means on the vehicle a distance in 80 the rear of the signal when it indicates absolute stop.

98. In a train control system, the combination with an interlocked signal, brake control apparatus on a vehicle including permissive speed means changeable to establish successively lower speed limits, and means partly on the vehicle and partly on the track for causing a change of said permissive speed means on the vehicle as it passes a point braking distance in the rear of the signal when the signal indicates absolute stop.

99. In a train control system, the combination with an interlocked signal, apparatus on a vehicle for governing the brakes thereof including changeable permissive speed means and a speed responsive device, and manually controllable means partly on the vehicle and partly on the track for governing said apparatus at a control point braking distance in the rear of the signal.

100. In a train control system, the combination with an interlocked signal, brake control apparatus on a vehicle including a speed responsive device and continuing in operation until restored, manually controllable means for arresting the operation of said apparatus at a distance in the rear of the signal, and traffic controlled means adjacent to the signal and also governed by the manually controllable means for restoring said apparatus.

101. In a train control system, in combination with a manually controlled interlocked signal, a track element braking distance in the rear thereof, a source of current and an energized circuit for said element, track circuits for closing and opening said circuit in accordance with traffic conditions, and manually controllable means for independently controlling said circuit to conform with the indication of said signal.

102. In a train control system, in combination with a manually controlled interlocked signal, a track element at a distance in the rear of said signal, vehicle carried means influenced by said element when it travels in the normal direction of traffic regardless of which end of the vehicle is ahead, a control

circuit for said element, and means for controlling said circuit to conform with the indication of said signal.

103. In a train control system, in combination with a manually controlled interlocked signal normally at stop, a distant track element, a control circuit therefor, and manually operable means for clearing the signal and closing the circuit.

104. In a train control system, in combination with an interlocked signal, brake control apparatus on a vehicle, traffic controlled trackway means adjacent to the signal for influencing the apparatus on the vehicle before it passes the signal, and other trackway means encountered by the vehicle after it passes the signal for arresting the movement thereof irrespective of speed, and manually controllable means for governing said trackway means.

105. In a train control system, in combination with an interlocked signal, separate permissive and absolute brake control means on a vehicle, trackway means adjacent to the signal and arranged to influence said permissive brake control means before the vehicle passes the signal, other trackway means at the signal for influencing the absolute brake control means on the vehicle after it passes the signal, and means for controlling both of said trackway means.

106. In a system of automatic train control, a roadway, a vehicle adapted to travel thereon, automatic stop devices carried thereby, said roadway comprising, automatically controlled zones adapted to control said automatic stop devices whereby, to prevent their operation, the operator of said vehicle is compelled to reduce its speed in accordance with predetermined speed reduction curves when approaching a zone of hazard traveling in the normal direction of traffic, automatically controlled zones adapted to control said automatic stop devices whereby, to prevent their operation, the operator in addition to reducing the speed of said vehicle in accordance with predetermined speed reduction curves, is compelled to absolutely stop said vehicle when approaching a zone of extreme hazard, and means to annul said automatic stop devices when said vehicle travels in a direction against the normal direction of traffic irrespective of which end of the vehicle is foremost, substantially as described.

107. In a system of automatic train control, a vehicle, a roadway therefor, means for automatically stopping said vehicle, automatically controlled zones on said roadway adapted to control said automatic stop means whereby, to prevent their operation the operator of said vehicle is compelled to reduce its speed in accordance with predetermined speed reduction curves when approaching a zone of hazard, and automatically con-

trolled zones on said roadway adapted to control said automatic stop means whereby to prevent their operation the operator of said vehicle, in addition to reducing its speed in accordance with said speed reduction curves, is compelled to absolutely stop said vehicle when approaching a zone of extreme hazard, substantially as described.

108. In a system of automatic train control, a vehicle, a roadway therefor, means for automatically stopping said vehicle, automatically controlled zones on said roadway adapted to control said automatic stop means whereby, to prevent their operation the operator of said vehicle is compelled to reduce its speed in accordance with predetermined speed reduction curves when approaching a zone of hazard traveling in the normal direction of traffic, automatically controlled zones on said roadway adapted to control said automatic stop means whereby, to prevent their operation the operator of said vehicle, in addition to reducing its speed in accordance with said speed reduction curves, is compelled to absolutely stop said vehicle when approaching a zone of extreme hazard traveling in the normal direction of traffic, and means for annulling the control of said automatic stop means by said controlling zones whereby said vehicle may travel without automatic control in a direction against the normal direction of traffic irrespective of which end of the vehicle is foremost, substantially as described.

109. In a train control system, a road bed divided into block sections, a vehicle adapted to travel thereon, means for automatically controlling the movement of said vehicle from said road bed, the functioning of said means being normally dependent upon the movement of other vehicles in advance of said vehicle when traveling in the normal direction of traffic and independent of the presence of other vehicles when the movement of said vehicle is in a direction against traffic regardless of which end of the vehicle is foremost, and means carried by said vehicle for rendering ineffective said functioning of said controlling means whereby a vehicle may move without automatic control in a direction "against traffic".

110. In a train control system, a road bed divided into block sections, a vehicle adapted to travel thereon, electro-magnetically controlled means for automatically controlling the movement of said vehicle over said road bed, a plurality of sources of current adapted to energize said electro-magnetic means whereby said automatic means is adapted to control said vehicle when traveling on said road bed in a normal direction of traffic, and means for establishing a corresponding number of energizing circuits whereby said automatic means is rendered ineffective to control said vehicle when traveling on said road

bed in a direction against the normal direction of traffic.

111. In a train control system, a road bed divided into block sections, a vehicle adapted to travel thereon, means for automatically controlling the movement of said vehicle from said road bed, the functioning of said means being normally dependent upon the movement of other vehicles in advance of said vehicle when traveling in the normal direction of traffic and independent of the presence of other vehicles when traveling in a direction against normal traffic, means carried by the vehicle for rendering ineffective said functioning of said controlling means whereby the vehicle may move without automatic control in a direction against normal traffic, and means carried by the vehicle whereby the vehicle operator will be warned of the fact that he is traveling in an "against traffic" direction.

112. In a train control system, a road bed divided into block sections, a vehicle adapted to travel thereon, means for automatically controlling the movement of said vehicle from said road bed, the functioning of said means being normally dependent upon the movement of other vehicles in advance of said vehicle when said vehicle is traveling in the normal direction of traffic, and independent of the presence of other vehicles when traveling in a direction against normal traffic, means carried by the vehicle for rendering ineffective said functioning of said controlling means whereby the vehicle may move without automatic control in a direction against normal traffic, and means carried by the vehicle whereby the vehicle operator will be warned of the fact that he is traveling in a direction contrary to normal traffic said last named means being inoperative when the vehicle is traveling in the normal direction of traffic.

113. In a train control system, a road bed divided into blocks, a vehicle adapted to travel thereon, means for automatically controlling said vehicle from said road bed when said vehicle is traveling in a normal direction of traffic, and means normally inoperative when said vehicle is traveling in

the normal direction of traffic but adapted to operate when said vehicle travels in a direction against the normal direction of traffic regardless of which end of the vehicle is foremost.

114. In a train control system, a road bed divided into blocks, a vehicle adapted to travel thereon, means for automatically controlling said vehicle from said road bed when said vehicle is traveling in a normal direction of traffic, and means carried by said vehicle which are normally inoperative when said vehicle is traveling in the normal direction of traffic but adapted to automatically operate when said vehicle travels in a direction against the normal direction of traffic regardless of which end of the vehicle is foremost.

115. In a train control system, a road bed divided into blocks, a vehicle adapted to travel thereon, means for automatically controlling said vehicle from said road bed when said vehicle is traveling in a normal direction of traffic, means carried by said vehicle normally inoperative when said vehicle is traveling in a normal direction of traffic but adapted to automatically operate when said vehicle travels in a direction against the normal direction of traffic and means for indicating the operation of the said last named means.

116. In a train control system, a road bed divided into block sections provided with indicating means, a vehicle adapted to travel thereon, means for automatically controlling the movement of said vehicle from said road bed, a stick circuit for rendering ineffective said controlling means when said train is traveling between indicating points, a ground circuit for rendering ineffective said controlling means when said train passes by means for giving an indication from the road bed to said train when proceeding under clear signals in a "with traffic" direction, and an against traffic retaining circuit for rendering ineffective said controlling means when said train passes by means for giving an indication from the road bed to said train when proceeding in an against traffic direction.

WINTHROP K. HOWE.
